UNITED STATES PATENT OFFICE.

WILLIAM C. CAMENISCH, OF CHICAGO, ILLINOIS.

DESIGN FOR A FIREPLACE-FRONT.

SPECIFICATION forming part of **Design No. 27,157**, dated June 1, 1897.

Application filed April 16, 1897. Serial No. 632,516. Term of patent 7 years.

To all whom it may concern

Be it known that I, WILLIAM C. CAMENISCH, a citizen of the United States, residing at Chicago, Illinois, have invented and produced a new and original Design for Fireplace-Fronts, of which the following is a specification.

This invention relates to a new and original design for fireplace-fronts; and the leading feature of the design consists in an ornamental front of rectangular outline surrounded by an ornamental border and having its interior divided into a series of panels of alternate open and closed work.

My design is illustrated in the accompanying drawing, which is a front elevation.

In said drawing, let A represent an ornamental border into which is worked the conventional floral representations *a* and a number of figures *b*. Said panel extends along the vertical sides and across the top of the front and may be surmounted by the band of geometrical figures B and the ornamented cap C.

D is a panel, subdivided by the diagonal lines *d d'*, with the open interiors surrounded by the scrolls *d²*. A panel A', of the same configuration as the border, joins the vertical members of the latter, and above said panel A' is a panel E, subdivided by rows *e e'* of ornamental work, subdividing said panel into a number of diamond-shaped figures having open interiors.

Inclosed by the upper portion of the border is a panel F, having the floral ornamentation *f*.

Having thus fully described my new and original design, what I claim, and desire to secure by Letters Patent, is—

The design for a fireplace-front, the same consisting of the design substantially as hereinafter shown and described.

WILLIAM C. CAMENISCH.
